UNITED STATES PATENT OFFICE.

CORNELIUS CALLAHAN, OF CHELSEA, MASSACHUSETTS, ASSIGNOR OF TWO-
THIRDS OF HIS RIGHT TO EDWIN E. SIBLEY, OF SAME PLACE.

IMPROVEMENT IN HOSE.

Specification forming part of Letters Patent No. **222,770**, dated December 23, 1879; application filed November 3, 1879.

To all whom it may concern:

Be it known that I, CORNELIUS CALLAHAN, of Chelsea, county of Suffolk, State of Massachusetts, have invented an Improvement in Hose, of which the following description, in connection with the accompanying drawing, is a specification.

My invention relates to suction-hose, and is an improvement on the suction-hose invented by me for which Letters Patent of the United States No. 218,661, dated August 19, 1879, were granted, to which reference may be had.

My present invention consists in a multi-ply suction-hose, consisting of several independent layers of tubular hose fabric, one or more of which has a metallic weft, the said tubular layers of hose-fabric being placed one outside the other, the said layers, one or more, having between them a coating of india-rubber, the said india-rubber being preferably located between the outside of the inner layer of fabric and the inner side of the next outer layer of fabric.

When the rubber coating is placed on the inside of knit or woven suction-hose next the water, as now common, the pressure of the atmosphere from the outside through the interstices of the fabric, acting upon the outer side of the india-rubber lining, resulting from the suction upon the inner side, is liable to tear the coating from the fabric, and thus seriously injure the hose.

If the rubber coating is placed on the outside of the innermost tubular layer of fabric, and then another slightly larger tube is drawn over the india-rubber, the latter is thoroughly protected.

The patent referred to shows a knitted hose having a series of independent warp-threads and two independent helices of wire-weft running through the fabric, these forming the entire weft of the fabric.

I have found that the flexibility of the hose may be greatly enhanced, and yet leave it strong enough to resist crushing, by using but one helix of wire, the coils of which are alternated with those of a fibrous-weft helix of proper size.

The tubes having been thus formed of suitable size, that one intended for the interior of

the suction-hose is coated on the outside in the usual manner with sheet-rubber, and a second tube like the first, but with its helices preferably inclined in the opposite direction to that of the interior tube, and large enough to slip over the outside of the first or rubber-coated tube, is drawn upon said rubber-coated tube; and, if desired, a third tube entirely of fibrous material, may be drawn upon the outside of the other two, with or without a second intermediate rubber coating, to thereby give a finished appearance and increased strength of hose.

My invention is herein shown as embodied in a knitted hose, the drawing showing, partly in longitudinal section, a sufficient portion of a multi-ply hose to fully illustrate my invention.

The inner tube, *a*, may be made on a machine the same as used in making the hose described in my former patent, and will be of similar construction, except that the coils *b* of the single helical weft of wire will be separated by the coils *c* of a fibrous helical weft-thread; but with the present arrangement of the rubber coating the fibrous covering for the wire weft, as described in said patent, may be omitted.

The rubber tube or coating *d* is placed on the outside of the knitted tube *a*, and vulcanized thereon in the usual manner.

The second tube, *e*, is precisely the same as the inner tube, *a*, except that it is larger in diameter, and that its helical weft is inclined opposite to that of tube *a*—that is, if the helices of tube *a* have the direction of the threads of a right-handed screw, those of tube *e* will have the direction of a left-handed screw.

This opposite arrangement of the wire weft tends to cause the hose to assume a straight-line position, and adds to the strength of the hose.

When desired, a third tube, *f*, formed entirely of fibrous material, may be drawn over the tubes *a e*, to give a finished appearance, form a jacket, and protect the inner main portions from wear.

It is obvious that the rubber coating *d* may be on the inside of the outer stiffened tube, *e*, instead of on the outside of the inner tube, *a*,

without departing from my invention, the essential feature of which is to place the rubber as an external coating for one of the two stiffened tubes, and to dispense with such coating on the inside of the hose, to thereby obviate the danger of said coating becoming detached, as described.

The independent warp-threads of the fabric are shown at *i*, and the enchain'd thread is indicated by the letter *m* in the drawing.

I claim—

1. As an improved article of manufacture, a multi-ply suction-hose, composed of two or more fibrous tubular-formed fabrics, one or more of which has a helically-arranged wire weft, and a tube or covering of vulcanized rubber external to one of the wire-wefted tubular fabrics, and between it and a surrounding tubular fabric, substantially as described, to prevent detaching the india-rubber tube by suction, as set forth.

2. In a multi-ply suction-hose, two or more tubes, substantially as described, provided with helically-laid weft of metal and fibrous

material alternately arranged, a coating of vulcanized india-rubber between them, and an outer tube entirely of fibrous material, substantially as described.

3. In a knitted suction-hose, provided with independent warp-threads, two independent helically-arranged wefts, one of metal and the other of fibrous material in alternate helices, said wefts being embraced by the knitted loops, as and for the purpose shown and described.

4. In a suction-hose, two or more knitted tubes, one within the other, each provided with a helically-arranged metallic weft, the helices of weft in the alternate tubes being inclined in opposite directions, substantially as described.

In testimony whereof I have signed my name to this specification in the presence of two subscribing witnesses.

CORNELIUS CALLAHAN.
